UNITED STATES PATENT OFFICE

WILLIAM T. CLARK, OF MILWAUKEE, WISCONSIN

SAFETY FEEDING DEVICE FOR CLOTHES WRINGERS

Application filed November 21, 1930. Serial No. 497,120.

The present invention relates to a safety feeding device acting co-operatively in association with a pair of compression rollers in a power operated machine. The said invention is designed particularly for use as an adjunct to the motor driven moisture-expressing rollers of a household laundry or clothes wringing machine. Its purpose is the provision of a mechanical device which 10 operates to feed the textiles to the compression rollers by which they are to be treated, with entire freedom from liability that the fingers of the operator of the machine will be caught between the rollers. I make a distinction between my invention, which functions freely as a feeding device in such manner that all danger is obviated, and prior safety feeding devices which are in the nature of guards in the use of which the feeding of 20 the textiles is not free, but is subordinate to the idea of preventing the fingers of the operator from being caught by the rollers of the machine.

In machines of the class to which the present invention pertains, in some of which there is no provision for mechanical feeding of the fabrics, the fingers of the hand of the operator are frequently caught between the rollers, and often with very serious consequences. The persisting presence of this danger has acted in a very large measure to detract from the popularity of the compression roller type of clothes wringer, and public favor is now swinging toward centrifugal extractors, in the use of which more work is required of the operator in effecting the desired results.

With a view to the elimination of the hazard mentioned, I have produced a safety feeding device of simple construction, also acting as a guard, which device is easily associated with clothes wringers of existing makes, and may be used with an assurance of absolute security against injury to the fingers of the operator.

In general, the invention resides in a bodily or laterally movable feeder bar, which is suitably mounted upon the frame of the clothes wringer in proximity to and parallel with the compression rollers thereof, which feeder

bar is normally in a retracted position of rest so as to be easily engaged by the wet textile which is to be passed between the moisture-expressing rollers of the wringer. The feeder bar supporting the leading end of the textile is moved manually toward the rollers, and the textile is entered into the bight of the rollers and drawn from the feeder bar. In so moving the feeder bar, the said bar is always between the hands of the operator and the compression rollers, so that it is not possible for the fingers of the operator to be accidentally caught by the rollers.

The feeder bar vibrates between stops, one of which, in fixed relation to the support for the bar, determines the normal retracted position of rest of the bar, and the other of which is adjustable on the support to control the extent of the forward feeding movement of the said bar and limit its entry into the space between the rollers.

In one form, the invention comprises a pivoted feeder bar which is moved laterally through a curved path at the time of its forward feeding movement. In another form, the feeder bar is mounted on guides so as to slide into position in its forward feeding movement. In all of its forms, the restoration of the bar to its normal retracted position of rest is a wholly automatic operation, induced by the gravitation of the bar, and in this lies the gist of my invention.

Having thus outlined the nature and purposes of my invention, I will now proceed to describe the same specifically, and in the appended claims will point out the novelty residing therein.

In the accompanying drawing:

Figure 1 is a view in front elevation of a clothes wringer, shown as a power driven extractor of the compression roller type, with my safety feeding device positioned thereon;

Fig. 2 is a plan view of the construction shown in Fig. 1, the feeder bar being shown as in its normal retracted position, that is, in the open position of rest in which it is adapted to receive a wet textile;

Fig. 3 is an enlarged sectional view transversely of Figs. 1 and 2, showing the feeder bar in its normal retracted position, or its po-

sition of rest, in full lines, and its abnormal or feeding position in dotted lines; and

5 Fig. 4 is an end view of a modified form of a construction in which my invention is embodied.

10 In the drawing, the numeral 10 indicates the framework of a clothes wringer equipped with moisture-expressing rollers 11 and 12, which are driven by the application of power through gear connections 13. Brackets 14 and 15 are attached to the front of the frame of the clothes wringer at its opposite ends, as indicated in Figs. 1 and 2. Each bracket is formed with a bearing 16, such bearings being provided for the reception of the opposite end journals of a feeder bar 17, the said bar being offset from the axis of its journals but extending parallel therewith. Elbows 18 and 19, preferably formed integrally with the feeder bar 17, connect the ends of the latter with the said end journals.

15 The inner faces of the brackets 14 and 15 are provided with stops 20 and 21, in substantial horizontal alignment with the bearings 16, and so positioned upon the brackets as to form outer stops for the feeder bar 17, when the latter drops through the influence of gravity to its normal retracted position, in which position it is adapted to receive an end 20 of the wet textile to be passed through the rollers.

25 The elbows 18 and 19 are recessed as at 22 on the surfaces nearest the expressing rollers. The brackets 14 and 15 are perforated for the 30 passage therethrough of a screw 23, the end of which is entered in a threaded opening eccentrically disposed in a disc 24, which latter is adapted to be received in the recess 22 in the elbow, to form inner stops for the feeder bar 17, when the latter is moved to effect a feeding operation. The purpose of the eccentric mounting just described is to enable an exact adjustment of the forward feeding movement of the bar 17 to be made, 35 as by changing the radius of the contacting point on the disc 24, which change is effected by rotating the discs 24 to the extent required, and setting them in position by tightening the screws 23.

40 In operation, with the feeder bar 17 in its normal retracted position of rest as indicated, one end of the wet textile is thrown over the bar, as indicated by the phantom in Fig. 3. The said bar is then lifted by a simple 45 hand movement, one finger under each end being sufficient, so that it is rotated about its journals from the full line receiving position shown in Fig. 3, to the dotted line delivering position there shown. In such latter position, the wet textile is carried into such proximity to the moisture-expressing rollers that its leading portion will be caught by the rollers and carried therebetween in the rotation of the latter. The construction and manner 50 of mounting of the feeder bar are such that

when freed from the textile which is passing through the rollers, the said bar will drop into its normal retracted position of rest, and will thus automatically position itself for the reception of another wet textile. The 55 automatic return of the feeding bar to its normal position of rest, is due to the construction wherein the center of gravity of the bar is always at one side of the vertical plane of the axis about which it turns, in any position of the bar. In other words, the journals are offset from the vertical plane of the bar.

60 Fig. 4 shows a modification of my invention in which the same principle of automatic restoration of the feeder bar to normal retracted position is effected. In this construction, I mount brackets 30, one of which is shown, upon the frame of the machine as before. Attached to each bracket is an arcuate guide 31, provided at its lower depending end with a retaining nut 32. The widened ends 33 of the feeder bar 171 are provided with outwardly projecting ears 34 and 35, each perforated so as to allow the feeder bar to slide freely on the curved guides 31. The feeding movement of the wet textile is the same as in the principal structure, and when released from the draft of the wet textile, the bar 171 will slide along the guides 31, automatically assuming its normal retracted position, as before. Adjustment of the extent of the feeding movement of the bar 171 in relation to the rollers may be made by placing shims 36, in any suitable number, upon the guides 31, in advance of the ear 34.

65 The surface curvature of the feeder bar tends to spread the wet fabric uniformly over the entire linear area of the feeder bar, and prevent it from bunching while passing through the rollers. The transverse flanges 37 at the ends of the active surface of the feeder bar, confine the wet textile to the desired path of movement while being drawn through the compression rollers.

70 The safety feeding device is applicable to either side of the clothes wringer and may easily be arranged to meet the requirement for convenient operation.

Having thus described my invention, what I claim and desire to secure by Letters Patent of the United States, is:

75 1. In a device of the class described, a frame, a pair of moisture-expressing rollers mounted thereon, and a normally retracted laterally movable pivoted bar for supporting and feeding a wet textile between the said rollers, the center of gravity of the said bar being at one side of the vertical plane of the axis of the bar, whereby when the textile is drawn from the bar by the rollers, the bar will automatically resume its normal retracted position.

80 2. In a device of the class described, a frame, a pair of moisture-expressing rollers mounted thereon, and a gravitating laterally

movable pivoted bar for supporting and feeding a wet textile between the said rollers, the center of gravity of the said bar being at one side of the vertical plane of the axis of the bar, whereby when the textile is drawn from the bar by the rollers, the bar will gravitate into its normal retracted position.

3. In a device of the class described, a frame, a pair of moisture-expressing rollers mounted thereon, a pivoted, laterally movable bar for supporting and feeding a wet textile between the said rollers, and brackets attached to the frame and supporting the said bar in a normal retracted position to receive a wet textile and for permitting the feeding movement of the bar, the center of gravity of the said bar being at one side of the vertical plane of the axis of the bar, whereby when the textile is drawn from the bar by the rollers, the bar will return to its normal retracted position.

4. In a device of the class described, a frame, a pair of moisture-expressing rollers mounted thereon, a laterally movable pivoted bar for supporting and feeding a wet textile between the said rollers, brackets attached to the frame for supporting the said bar in a normal retracted position to receive a wet textile and for permitting the feeding movement of the bar, the center of gravity of the said bar being at one side of the vertical plane of the axis of the bar, and means on the brackets for limiting such feeding movement, whereby when the textile is drawn from the bar by the rollers, the bar will automatically resume its normal retracted position.

5. In a device of the class described, a frame, a pair of moisture-expressing rollers mounted thereon, a gravitating, laterally movable pivoted bar for supporting and feeding a wet textile between the said rollers, means for supporting the said bar in a normal retracted position to receive a wet textile and for permitting the feeding movement of the bar, the center of gravity of the said bar being at one side of the vertical plane of the axis of the bar, and means for limiting such feeding movement, whereby when the textile is drawn from the bar by the rollers, the bar will gravitate into its normal retracted position.

In testimony whereof, I have signed my name at Milwaukee, this 15th day of November, 1930.
